UNITED STATES PATENT OFFICE.

FRANK G. HOLMES, OF TRENTON, NEW JERSEY, ASSIGNOR, BY DIRECT AND MESNE ASSIGNMENTS, OF ONE-HALF TO THE ARCHIBALD-KLEMENT COMPANY, OF NEWARK, NEW JERSEY, A CORPORATION OF NEW JERSEY, AND ONE-HALF TO LENNOX INCORPORATED, OF TRENTON, NEW JERSEY, A CORPORATION OF NEW JERSEY.

DESIGN FOR A VESSEL FOR TABLE USE.

No. 38,324.

Specification for Design.

Patented Nov. 27, 1906.

Application filed May 22, 1906. Serial No. 318,262. Term of patent 7 years.

To all whom it may concern:

Be it known that I, FRANK G. HOLMES, a citizen of the United States, residing at Trenton, in the county of Mercer and State of New Jersey, have invented an original and ornamental Design for a Vessel for Table Use, of which the following is a specification, reference being had to the accompanying drawings, forming a part thereof.

In the drawings I show in Figure 1 a side elevation of a vessel for table use embodying my design, and in Fig. 2 I show a top view of such vessel.

As appears from said figures, the design comprises, essentially, a vessel of polygonal shape (hexagonal in the particular instance shown) as viewed from above, the horizontal lines of each of the faces of such vessel being approximately straight. As viewed from the side, the vessel, beginning at the bottom or base, comprises an upwardly-tapering portion merging by a smooth concave curve into a main body portion much larger than the base, which body portion again contracts near the top and finally expands by a smooth

curve to near the top of the vessel. The outline of each edge of the vessel as viewed from the side is that of a smooth ogee curve comprising two concave curves with an interposed convex curve. I use this design in the various vessels of tea sets and the like, the several vessels all having the characteristics above mentioned, but having the differences in size, proportions, and attachments required or desirable to adapt them to their several functions.

In my applications filed May 22, 1906, Serial Nos. 318,264 and 318,265, I show, respectively, a coffee-pot and a teapot embodying the above-described design, with the addition of top, handle, and spout, as required.

I claim—

The ornamental design for a vessel for table use, as shown and described.

FRANK G. HOLMES.
